UNITED STATES PATENT OFFICE.

ISAAC J. MARCUSE, OF RICHMOND, VIRGINIA, ASSIGNOR TO AMERICAN CAN COMPANY,
OF NEW YORK, N. Y., A CORPORATION OF NEW JERSEY.

DESIGN FOR A SHEET-METAL POCKET TOBACCO-BOX.

41,984.

Specification for Design.

Patented Dec. 19, 1911.

Application filed September 18, 1909. Serial No. 518,457. Term of patent 14 years.

To all whom it may concern:

Be it known that I, ISAAC J. MARCUSE, of the city of Richmond, in the county of Henrico, in the State of Virginia, have invented a new, original, and ornamental Design for a Sheet-Metal Pocket Tobacco-Box, of which the following is a specification, reference being had to the accompanying drawing, forming a part thereof.

The figure is a perspective view of a sheet

metal pocket tobacco box showing my new design.

I claim:

The ornamental design for a sheet metal pocket tobacco box, as shown.

ISAAC J. MARCUSE.
